Primary Examiner — Susan Moon Lee*(74) Attorney, Agent, or Firm* — Global IP Counselors, LLP(57) **CLAIM**

The ornamental design for a litter scoop, as shown and described.

DESCRIPTION

FIG. 1 is a top perspective view of a litter scoop in accordance with my new design;

FIG. 2 is a bottom perspective view thereof;

FIG. 3 is another bottom perspective view thereof;

FIG. 4 is a top view thereof;

FIG. 5 is a bottom view thereof;

FIG. 6 is a right side view thereof;

FIG. 7 is a left side view thereof;

FIG. 8 is a front view thereof; and,

FIG. 9 is a back view thereof.

The contour lines depict illustration only, and form no part of the claimed design.

The broken lines shown represent unclaimed features of the litter scoop depicted for purposes of illustration and that form no part of the claimed design.

1 Claim, 9 Drawing Sheets(56)
